UNITED STATES PATENT OFFICE.

RALPH E. WILLIAMS, OF LOS ANGELES, CALIFORNIA.

DESIGN FOR AN ELECTRIC-LAMP HANDLE AND SUPPORTING-BRACKET.

55,349.

Specification for Design.

Patented May 25, 1920.

Application filed April 23, 1918. Serial No. 230,351. Term of patent 14 years.

To all whom it may concern:

Be it known that I, RALPH E. WILLIAMS, a citizen of the United States, residing at Los Angeles, in the county of Los Angeles, State of California, have invented a new, original, and ornamental Design for an Electric-Lamp Handle and Supporting-Bracket, of which the following is a specification, reference being had to the accompanying drawing, forming a part thereof.

The figure is a perspective view of an electric lamp handle and supporting bracket, showing my new design.

I claim:

The ornamental design for an electric lamp handle and supporting bracket, as shown.

RALPH E. WILLIAMS.
